UNITED STATES PATENT OFFICE.

OLIVER H. HAMPTON, OF WILLIAMSBURG, INDIANA.

ACETYLENE-GAS APPARATUS.

SPECIFICATION forming part of Letters Patent No. 674,698, dated May 21, 1901.

Application filed June 28, 1900. Serial No. 21,872. (No model.)

To all whom it may concern:

Be it known that I, OLIVER H. HAMPTON, a citizen of the United States, and a resident of Williamsburg, in the county of Wayne and State of Indiana, have invented a new and Improved Gas-Machine, of which the following is a full, clear, and exact description.

This invention relates to improvements in acetylene-gas machines; and the object is to provide a gas-machine of novel construction in which the gas will be automatically generated and in which there will be no danger of bursting by overpressure, and, further, to provide a means for automatically maintaining a uniform water-level in the generator.

I will describe a gas-machine embodying my invention and then point out the novel features in the appended claims.

Reference is to be had to the accompanying drawings, forming a part of this specification, in which similar characters of reference indicate corresponding parts in all the figures.

Figure 1 is a sectional elevation of a gas-machine embodying my invention. Fig. 2 is a horizontal section of part of the same, and Fig. 3 is a section on the line 3 3 of Fig. 1.

The generator comprises a cylinder 1, upon which is arranged a water-tank 2, the said water-tank having a depending flange 3, designed to engage closely in the upper portion of the cylinder 1 and extending below the water-line thereof, thus preventing any possible escape of gas except through an overflow-pipe the upper end of which, outside of the cylinder 1, is extended out of doors. Extended upward from the bottom of the water-tank 2 and nearly to the top thereof is a pipe 4, and a pipe 5, having a funnel-top 6, is extended through the top of the water-tank downward within the pipe 4 and nearly to the bottom thereof. Also extended through the top and bottom walls of the water-tank is a feed-pipe 7, having perforations 8 slightly above the bottom wall of the water-tank and adapted to be closed by a piston-valve 9, having a stem 10, extended upward through the pipe or tube 7. A valve-controlled vent-pipe 11 is arranged at the top of the water-tank.

Removably placed in the cylinder 1 is a tray-case 13, closed at the bottom and open at the top. Within the tray-case is arranged a series of carbid containers or trays 14, formed

into compartments, the said trays being arranged one above another, and each tray is provided with bails 15 for convenience in removing it from the tray-case. Each tray is provided with a water-inlet 16 near its upper edge, and it will be noted that the tray-case is provided with a water-opening 18 near the top. The upper open end of the tray-case is closed by the top 21 of the water-seal jacket 12. At the center of the top 21 is a dome 20, into which pipes 19 and 25 are carried above the water-level in the cylinder 1. Within the dome the top 21 is provided with apertures, as indicated by an arrow, through which gas may pass into the dome. The jacket is removably clamped over the tray-case by means of the jacket-pipe 19, the lower end of which is fastened to the bottom of the tray-case, and the upper threaded end of said pipe 19 engages in a screw-threaded opening 26 in the top 21 within the dome, so that by rotating the jacket 12 it may be screwed down and held tightly in position.

The bottom of the carbid-holder is provided with angular legs 22, the horizontal portions of which are designed to engage underneath keepers 23, secured to the inner side of the cylinder 1, and these legs are also designed to rest upon brackets 24, arranged within the cylinder for a purpose to be hereinafter described.

The gas-pipe 25 passes upward through the jacket-pipe 19 and above the water-level, and an overflow-pipe 27 is arranged in the cylinder 1 to carry off water should the same rise above the required level. The gas-feed pipe 25 leads into a gasometer consisting of a fixed cylinder 28, in which is movable the bell 29. The pipe 25 connects with a pipe 30, extended vertically in the gasometer, and in the upper portion of this pipe 30 is a valve 31, to the stem of which a lever 32 is attached, the said lever being extended into a longitudinally-slotted rod 33, arranged in the gasometer. A by-pass or tube 34 communicates with the pipe 30 below the valve 31 and is then extended upward and then downward, its lower end terminating below the water-level in the gasometer. From the gasometer the gas passes through a pipe 35, which communicates with an outlet-pipe 36.

In operation the above-described carbid-

holder will be submerged in the water contained in the cylinder and held in that position by the angular legs engaging underneath the keepers 23. It will be seen that the water will try to reach the same level both inside and outside of the carbid-holder and that it will rise between the walls of the tray-case 13 and the walls of the jacket 12 unless prevented by air or gas within the space between the walls of the tray-case and the jacket, and if the head of water in the cylinder 1 be high enough the water-pressure will drive the air or gas that is between the walls through the opening 18 in the tray-case and be followed by the water, which will run down through a boxing X, attached to the inner side of the tray-case, and over the opening 18, passing through an opening 17 at the lower end of the boxing X, and will fill beneath and around the lowest tray till it has risen to the water-inlet 16 in the side of the tray, and thence into the first carbid-compartment of the tray-case, and the generated gas will pass out through the opening of the tray and into the gasometer through the pipes 25 and 30. The flow of water and the production of gas will continue uninterruptedly so long as the relative conditions of water-head and gas-pressure remain the same; but if the head of water be sufficiently decreased or the gas-pressure sufficiently increased, so that the gas-pressure is the strongest, it will hold the water below the water-opening 18, and further gas generation must cease for lack of water.

In connection with this device there is shown in Fig. 1 an ordinary storage-gasometer, whose inlet-pipe 30 is fitted with a valve 31, operated by the lever 32, operated by the channel-bar 33, which rises and falls with the gasometer-bell 29. When the valve 31 is open, as shown in the drawings, gas can pass freely into the gasometer, and a sufficient water-head being maintained from the reservoir 2 gas-making proceeds until the accumulation of gas under the gasometer-bell closes the valve 31, and any gas made after the valve is closed must go through the by-pass 34, which has its outlet end immersed in the water, and the resistance of the water raises the pressure in the carbid-holder sufficiently to hold the water that is between the walls of the tray-case and the jacket below the opening 18 in the wall of the tray-case, so that no more water can get to the carbid until the gas on hand is drawn off for use. The automatic production of gas can also be effected by establishing by means of the outlet-pipe 7 a water-level too low for the production of gas and using any suitable device for opening and closing the air-cock 11 as the gasometer-bell rises and falls or any other device which will pour a suitable quantity of water into the cylinder 1 as it is needed.

It is evident that a nearly-constant water-level must be maintained in the cylinder 1, and for this purpose I provide the reservoir

2. When the reservoir 2 is to be filled, the vent 11 must be opened and the valve 9 moved downward to close the openings 8. Then water poured into the pipe 5 will pass downward and then upward between said pipe 5 and the interior of the pipe 4 and over the upper end of said pipe 4. When the tank is filled, the water between the pipes 4 and 5 will form a seal to prevent the entrance of air. After filling the tank the vent 11 must be closed and the valve 9 is to be moved upward to open the perforations 8. If the water-level in the cylinder 1 is high enough to cover the lower end of the pipe 7, no water will flow through it; but whenever the end of said pipe is opened by the water falling below it the water will flow from the tank 2 into the cylinder.

As before stated, if from any cause the water-level gets too high in the tank it is carried off through the pipe 27.

When the carbid charge is to be renewed in the several holders, the said holders, with the tray and tank, are to be rotated, releasing the legs 22 from the keepers 23, and then by lifting the said parts upward the legs may be engaged on the brackets 24, which brings the top of the tray-case above the water-level, so it can be opened without water entering. Of course before this is done the water-tank 2 must be removed.

One advantage of the above-described apparatus is that the carbid-holder is entirely submerged in an ample quantity of water, and therefore the gas is kept cool. Another advantage is that the gas generation begins at the bottom and the gas is made to pass over the unused carbid, which absorbs the moisture from the gas.

Having thus described my invention, I claim as new and desire to secure by Letters Patent—

1. A gas-machine, comprising a generating cylinder, a tray-case removably arranged therein and having a water-inlet near its top, a boxing connected to the inner side of the tray-case over said inlet and having an opening at the bottom, a jacket around the tray-case and having a top forming a closure for the tray-case, a dome on the top of the jacket and communicating with the interior of the tray-case, means for removably securing the jacket in place and a series of carbid-trays arranged, one upon another, in the case, each tray having a water-inlet in its side, substantially as specified.

2. A gas-machine, comprising a generating cylinder, a tray-case arranged in the cylinder and having a water-inlet near its top, a jacket surrounding the case, the top of said jacket forming a closure for the case, a dome on said cover communicating with the tray-case through openings in the cover, the said cover having a screw-threaded opening within the dome, a jacket-pipe connected to the bottom of the tray-case and having a threaded upper end for engaging in said threaded opening, a gas-

discharge pipe leading through the jacket-pipe and extended into the dome and carbide-trays arranged in the case and surrounding the jacket-pipe, substantially as specified.

5 3. A gas-machine, comprising a generating-cylinder, carbide-holders arranged in the cylinder, a water-tank placed removably on the top of said cylinder, a pipe leading upward from the bottom of said tank, a pipe leading through the top of said tank and into the first-named pipe, there being a space between the two pipes, a pipe leading through the upper and lower walls of the tank, a valve for controlling perforations in the lower portion 15 of said pipe, and a vent for the tank, substantially as specified.

4. A gas-machine, comprising a generating-cylinder, a carbide-chamber removably placed therein, angle-legs connected with said carbide-chamber, keepers arranged on the cylinder underneath which the said legs are designed to engage, brackets in the cylinder upon which the legs may rest, and a gas-discharge pipe leading upward through the chamber, substantially as specified. 20 25

In testimony whereof I have signed my name to this specification in the presence of two subscribing witnesses.

OLIVER H. HAMPTON.
